SAFETY DEVICE FOR SEWING MACHINES

Michael McCann, Ozone Park, N. Y., assignor to
The Singer Manufacturing Company, Elizabeth, N. J., a corporation of New Jersey

Application March 31, 1942, Serial No. 436,971

2 Claims. (Cl. 192—139)

This invention relates to improvements in safety devices and particularly to safety devices which are adapted to be used in connection with sewing machine stop-motion mechanisms.

The object of the present invention is to prevent the repetition of a sewing machine stitching cycle in the event the operator inadvertently maintains the stop-motion control pedal depressed.

A further object of the present invention is the provision of an improved safety device in the form of an attachment which may be inexpensively constructed and readily applied to substantially any of the common types of sewing machines using a stop-motion mechanism, without the necessity of complex adjustment.

The foregoing objects, and others ancillary thereto, have been attained by the provision of an improved safety attachment including a supporting bracket carrying a pair of reciprocatory rods and a latch member carried thereon adapted to be secured to a sewing machine frame whenever a safety device is required and to be readily removable therefrom when such a unit is no longer desired.

The invention, both in structure and in operation, as well as additional objects thereof, will be best understood from the following description taken in conjunction with the accompanying drawing, in which:

Fig. 1 is a front perspective view of the present attachment, with the cover-plate removed, applied to a sewing machine.

Fig. 2 is a side view of the attachment with cover-plate removed.

Fig. 3 is a front view of the device as shown in Fig. 2.

Fig. 4 is a horizontal section view taken substantially along line 4—4 of Fig. 3.

Fig. 5 is a front view of a portion of the attachment in starting position.

Fig. 6 is an enlarged perspective view of the latch member and its supporting block.

Fig. 7 is a perspective view of the cover-plate.

Referring to the drawing 10 represents a sewing machine frame in which is journaled longitudinally thereof the usual main-shaft 11 from which is derived, through the usual operative connections, the reciprocating movements of a needle, not herein shown.

The stop-motion mechanism of the present machine is substantially the same as that shown in the United States patent to W. L. Barron, No. 1,093,241, of April 14, 1914. Upon the rearward

end portion of the main-shaft 11 are mounted the usual fast and loose pulleys 12 and 13. The stopping-cam 14 is also mounted upon and adapted to rotate with the shaft 11. Cooperating with the stopping-cam 14 is the plunger-bar 15 mounted within the swinging stop-lever 16 fulcrumed within the slotted boss 24 of the bracket 18. The stop-lever 16 carries the belt-shifter arm 19. Mounted upon the pivotal pin 20 of the bracket-arm 17 is the angular shift-lever or operative means 21 for tilting the stop-lever 16 in opposition to its spring 22 to shift the driving belt, not herein shown, from the loose pulley 13 to the tight pulley 12 and disengage the plunger-bar 15 from the stopping-cam 14.

The stop-lever 16 is detained in running position by the usual latch means 23 which is adapted to thus retain the stop-lever in running position until the stitching cycle is terminated at which time the stop-lever is released, and under the pressure of the spring 22 shifts outwardly to engage the plunger-bar 15 with the stopping-cam 14, all in the usual manner.

It may therefore be understood that when the shift-lever 21 is moved downwardly by the operator, the stop-lever 16 is swung inwardly thereby throwing the machine into operation. As hereinabove noted, the stop-lever 16 is held latched in this position until it is automatically released at the end of the stitching cycle.

In a high speed machine of the present type which is adapted for producing groups of tacking stitches and the like, only a few seconds elapse between the starting of the machine and the completion of one stitch-group. It frequently happens therefore that the operator, by continuing to hold the treadle or manipulative means depressed, prevents the spring 22 or the like from promptly moving the stop-lever 16 into stopping position, thereby resulting in defective work, or in the breakage of machine parts. The use of the present safety device obviates this difficulty.

As noted above the stop-lever 16 is pivotally mounted in the outwardly projecting and slotted boss 24 to which a flange 25 is mounted by means of screws one of them being designated by number 26. Pivotally carried by flange 25 by means of a bolt 27 is a lug 28 which projects from the rear portion of the supporting bracket 29. The bolt 27 passes through apertures 52 and 53 provided respectively in the flange 25 and the lug 28. This supporting bracket comprises a substantially C-shaped member the projecting

arms 30 and 31 of which are spaced from and are in parallelism with each other.

The arms 30 and 31 function as bearing members in which are slidably received the parallel first and second rods 32 and 33. The second rod 33 at its upper end normally projects above the upper portion of the bracket, and is pivotally connected to a link 34 which in turn is similarly connected directly to the stop-motion shift-lever 21. The first rod 32 at its lower end normally projects below the lower portion of the bracket and is connected to the upper end of a chain 35 which normally is connected to the usual stop-motion control lever or pedal, not herein disclosed.

Pivottally mounted in spaced positions upon the upper portion of the first rod 32 is a bifurcated latch-lever 36 which is shiftable about the longitudinal axis of the rod and restrained from endwise movement thereon by means of a block 37 embraced by said latch-lever and secured to the rod by means of the set-screw 38. Secured upon the latch-lever 36 by means of a screw 39 is a leaf spring 40 one end of which engages the block 37 to force the latch-lever against the second rod 33 thereby to overlie and engage an abutment member 41 carried by rod 33 and made rigid thereto by means of a set-screw 42. Downward movement of the first rod 32 will, therefore, because of this latch-lever and abutment engagement, actuate the second rod 33 also in a downward direction. Surrounding the lower portion of rods 32 and 33 are coil compression springs 43 and 44 which constantly urge the respective rods upwardly. The lower ends of springs 43 and 44 engage the bearing member 31 and the upper ends of the springs respectively engage the base of the latch-lever 36 and the abutment member 41.

During the downward movement of the rods, as actuated by a pull on chain 35, the latch-lever 36 engages the slanted cam surface 45 of a stationary trip-member 46 which is fixed to the bracket 29 by means of screws 47. Further downward movement of the rods will permit the cam-surface 45 to turn the latch-lever 36 about the longitudinal axis of the first rod in opposition to its spring 40 until it rides off the abutment member 41, whereby the second rod is released from further downward motion and it returns to its normally raised or starting position under the action of its coil-spring 44.

Figs. 2 and 3 disclose, in solid lines, the attachment the moment that the latch-lever 36 first engages the trip-member 41 and in broken lines, the relative positions of the component parts the moment after the latch has been opened thereby permitting the rod 33 to move to its starting position.

It is to be understood that the initial downward movement of the manually operable chain 35 shifts both rods 32 and 33 downwardly in unison and consequently actuates the shift-lever 21 to start the machine, and when the two rod members are released from each other, as described above, the stop-motion mechanism will automatically be freed from its manually operable chain 35 so that it may unfailingly stop the machine at the end of the sewing or machine operation. Upon release of the chain 35 by the operator, the first rod is raised by its spring 43 to its normal or starting position, as shown in Fig. 5, in which it again is re-connected to the second arm member.

When the stop-lever 16 is shifted into starting

position by a downward movement of the shift-lever 21 it engages the latch member 23 which retains the stop-lever in this position until the stitching cycle is terminated at which time the stop-lever is released under pressure of spring 22.

Downward movements of rod 32 is limited by a nut 48 threaded upon the top portion thereof and its upward movements are arrested by means of a lug 49 secured upon the bottom portion thereof. Upward movements of rod 33 is limited by a nut 50 threaded upon its lower portion.

In order to properly enclose the operating mechanism of the present device a cover-plate 51 is provided which is adapted to be slid lengthwise over the bracket 29 and to be retained thereon by means of its narrow head 52. In the preferred form of the device this cover-plate is constructed of a resilient sheet-metal which permits the cover-plate to be readily snapped over and removed from the bracket 29.

To attach the safety device unit to a sewing machine the user need only secure the flange 25 to the machine boss 24 by means of screws 26 and then connect the link 34 to the shift-lever 21 by means of a pivot pin 53. To make the safety device operative, the chain 35 may be suitably connected to the usual stop-motion treadle.

From the above description it is obvious that this safety device is readily adaptable to substantially all sewing machines which are provided with stop-motion mechanisms. Likewise, it will be apparent that the device may be readily placed on and removed from operative position by a few simple hand movements, while at the same time, it provides a compact and efficient machine actuating device. It is also of particular import to note that the component parts of the present invention are designed so that a most simple and rugged construction results. Furthermore, the device requires no expensive machining operations in its production as the parts thereof may be readily cast or pressed into their final form.

Having thus set forth the nature of the invention what I claim herein is:

1. In a safety device of the class described, comprising, a bracket, a first and a second rod disposed in parallelism with each other and mounted for endwise movement in said bracket, a pair of coil springs disposed within said bracket, each of said coil springs surrounding a portion of and engaging a respective one of said first and second rods to spring bias said rods in the same direction, an abutment member mounted upon said second rod, a trip-member carried by said bracket, and a latch-supporting block rigidly mounted upon said first rod; the improvement which consists in the provision of a bifurcated latch member pivotally engaging said first rod in spaced positions and surrounding said latch-supporting means, said member being shiftable about the longitudinal axis of said first rod, and a leaf spring having one end secured upon said member and the other end thereof engaging said latch-supporting block to spring bias said member against said second rod and in engagement with said abutment member.

2. A safety device of the class described, comprising a C-shaped bracket, the arms of said bracket being bearing members, a first and a second rod mounted for endwise movements within said bearing members and being disposed in parallelism with each other, a pair of coil

springs disposed between said bearing members, each of said coil springs surrounding a portion of and engaging a respective one of said first and second rods to spring bias said rods in the same direction, a block secured upon said first rod, a bifurcated latch member pivotally engaging said first rod in spaced positions and embracing two opposing sides of said block so as to be shiftable about the longitudinal axis of said first rod, an abutment member secured upon said second rod, a leaf spring disposed lengthwise of said latch member and having one end thereof secured

upon said latch member and its other end engaging said block to spring bias said latch member toward said second rod and in engagement with said abutment member, and a trip-member fixed upon the side of said bracket to be engaged by said latch member for pivoting the latter about the axis of said first rod in opposition to said leaf spring thereby to disengage the latch member from said abutment member upon a predetermined movement of said first rod.

MICHAEL McCANN.
